UNITED STATES PATENT OFFICE.

JAMES I. COMLY, OF PHILADELPHIA, PENNSYLVANIA.

HOUSE.

SPECIFICATION forming part of Letters Patent No. 540,639, dated June 11, 1895.

Application filed April 2, 1892. Serial No. 427,438. (No model.)

To all whom it may concern:

Be it known that I, JAMES I. COMLY, of the city of Philadelphia and State of Pennsylvania, have invented a certain new and useful 5 Improvement in Houses; and I do hereby declare the following to be a full, clear, and exact description thereof, reference being had to the accompanying drawings, forming part of this specification.

10 My invention has relation to the construction of houses and its advantages are manifest in such as have front and back buildings and are built in rows with a house or building adjoining them on each side, and consists 15 in the construction hereinafter described and claimed whereby a house has front and back buildings in which the front building of the first story is longer than the front building of the second or upper stories, and in which 20 the rear wall of the front building of the second and upper stories is in front of the rear wall of the first story front building and over the back room of the first story front building; and the side wall of the back building 25 in the second or upper stories is extended frontward also over the back room of the first story front building to the back wall of the front building of the second or upper stories.

The object of my invention is to provide a 30 floor space in all the stories of such a size and shape as to admit of convenient, symmetrical, well-lighted, and desirable interior divisions, and at the same time to economize in space and cost of construction.

35 In houses, as above mentioned, built in rows with front and back buildings, as usually constructed, the first story of the front building contains the parlor and hall, while the dining-room is generally in the back building 40 and is poorly lighted, the length of the parlor being in this construction the length of the front building in all the stories and is insufficient to make two, desirable-sized rooms over it in each of the second and upper stories.

45 In my construction the front building is made long enough in the first story to contain the parlor and hall, together with a dining-room in the rear. The same-sized front building in the second and upper stories would be undesirable, as the back one of the two rooms into which it would be divided in each story

would be too long and poorly proportioned; but, making the front building in the second and upper stories shorter than the front building in the first story by a distance less than 55 the dining room gives a convenient size to the back room of the front building in the second or upper stories, a part of its length of its full width, thus being directly above the dining-room, places the bath-room, while in 60 the back building of the second story, over the front building of the first story, giving it a communicating door with the back room of the front building and thus allowing the back stairway, by being placed back of the bath 65 room, to have a landing in the first story back of the dining room, and at the same time, by using the space of the ceiling of the back part of the front building of the first story left uncovered by making the front building 70 in the second and upper stories shorter than in the first story as a skylight or window in addition to the other window, giving to the dining-room much greater and sufficient light. In this construction, when the width instead 75 of the length of the dining room, as in the old way, is part of the length of the house, the total length is shortened; consequently the cost of construction is diminished. In Reissue Letters Patent No. 11,804, dated February 7, 80 1893, issued to me, I have claimed one method of construction whereby this result is obtained, and my present invention relates to another construction to obtain the same result. 85

In the accompanying drawings similar letters of reference refer to similar parts throughout.

Figure 1 is a plan view of the first floor of the building containing my improvement. 90 Fig. 2 is a plan view of the second floor. Fig. 3 is a side elevation of a building containing my improved construction, partially in section, on the line α α of Fig. 1.

A, A', are respectively the side walls of the 95 front building.

B is the front wall and B' the rear wall of the front building of the first story.

F is the partition dividing the front and back rooms of the first story front building. 100

C, C', are the side walls respectively of the back building. A girder, G, is supported at

one end in the wall, C, of the back building at or near the level of the second floor of the front building and extends longitudinally preferably on a line with the side wall, C, to 5 a point beyond the girder G' preferably at or near the partition dividing the front from the back room of the first story of the front building and is supported upon a pier, P, or a cross-girder, or by said partition, or other 10 suitable means. The cross girder, G', is supported at one end in the wall, A, at or near the level of the second floor of the front building at a desirable distance from the rear wall, B', of the front building of first story— 15 say six or seven feet—and extends latitudinally to the point of intersection with the longitudinal girder, G, to which it is secured by braces, bolting or otherwise, and by which it is at that end supported. Upon the girder, 20 G', is built the rear wall, B², of the second or upper floors of the front building, while the side wall, C, of the second and upper stories of the back building is continued and built upon a portion of the girder G, and connected 25 with the wall, B². It will thus be seen that the second and upper stories of the front building will not extend as far rearward as the first story of the front building. By this construction, the second story front building can 30 be divided into symmetrical rooms of nearly equal size, while the rooms of the first story front building can be properly proportioned for parlor and dining room. The rear room of the first story of the main building which is 35 above termed the "dining-room," can be advantageously lighted by a skylight S, constructed in the space where the wall B² recedes. A window may also be provided in the rear wall B'. 40 Having now fully described my invention,

what I claim, and desire to protect by Letters Patent, is—

1. In a dwelling house, a combination of the longitudinal wall, A, the longitudinal wall, C, and the partition, F, between the parlor and dining room, the longitudinal girder, G, one end being supported by the wall, C, the other end by a pier, cross girder or otherwise, the short transverse girder, G', one end supported by the wall, A, the other by the 50 girder, G, the rear wall, B², of the main building in the second story being supported by the girder, G', and a portion of the side wall, C, of the back building in the second story being supported by the girder, G, arranged in 55 the manner and for the purpose substantially as described.

2. A dwelling house having front and back buildings in which the first story front building is constructed into a front room or parlor 60 and a hallway together with a back room or dining-room in the rear, and in which the second story front building is shortened and the second story back building is lengthened by dividing between them that part of the 65 length of the house which in the first story is the dining-room, by constructing the wall, B², on the short transverse girder, G', and a part of the wall, C, on a portion of the longitudinal girder, G, and in which the full width 70 of the second story back building extends over a portion of the dining-room, substantially as described.

In witness whereof I have hereunto set my 75 hand this 1st day of April, 1892.

JAMES I. COMLY.
